CLAIM

The ornamental design for a mobile telephone, as shown and described.

DESCRIPTION

FIG. 1 is a top right perspective view of the mobile telephone according to a preferred embodiment;

FIG. 2 is a front elevational view thereof;

FIG. 3 is a rear elevation view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown throughout the views, which are immediately adjacent to the shaded areas and define unshaded regions, represent the bounds of the claimed design. All other broken lines, including the broken lines on the keys on the front, which are superimposed on continuous surfaces, are directed to environment and are for illustrative purposes only. The broken lines throughout the views form no part of the claimed design.
